CONTROL MECHANISM

Filed July 9, 1930

UNITED STATES PATENT OFFICE

CLARENCE B. CAMPBELL, OF MOORES, PENNSYLVANIA, ASSIGNOR TO WESTINGHOUSE ELECTRIC & MANUFACTURING COMPANY, A CORPORATION OF PENNSYLVANIA

CONTROL MECHANISM

Application filed July 9, 1930. Serial No. 466,797.

My invention relates to a control mechanism for a prime mover, more particularly to a control mechanism for a multi-stage elastic fluid prime mover having openings at two or more intermediate-pressure stages for extracting partially expanded motive fluid from the prime mover or for admitting motive fluid thereto, and it has for its object to provide an improved construction of such mechanism.

A more particular object is to provide an improved control mechanism of the character set forth which will, upon change in demand for flow of fluid through one of the openings, operate the valve means at said one opening to effect the desired change in flow and to maintain the desired pressure, and which will at the same time operate the admission valve and the valve means at the other opening to maintain the proper load on the prime mover and the proper flow and pressure at said other opening.

In accordance with my invention, I provide a control device associated with each opening which provides two fluid pressures varying in opposite directions to each other in response to variations in pressure at the opening. A regulating means for controlling the flow at each opening is responsive to that one of the fluid pressures of each control device whose variations are in the proper direction.

The above and other objects are effected by my invention, as will be apparent from the following description and claims taken in connection with the accompanying drawing, forming a part of this application, in which:

The single figure is a diagrammatic view of the control mechanism applied to a multi-stage fluid turbine.

Referring now to the drawing more in detail, I show an elastic fluid turbine 10 having a casing 11 and a rotor 12. The turbine is supplied with motive fluid, which may be any suitable elastic fluid, such as steam, from a conduit 13 and the admission thereof to the turbine is controlled by an admission valve 14.

The turbine 10 is designed for operation in connection with demand for elastic fluid

at two different pressures below the pressure at which motive fluid is admitted to the turbine. For example, elastic fluid at pressures of 125 lbs. per sq. inch and 8 lbs. per sq. inch may be required, while elastic fluid may be admitted to the turbine at a pressure of 400 lbs. per sq. inch. The expansion from the latter pressure to either of the lower pressures is utilized in the turbine to develop power.

The casing 11 is formed with an opening 15, at an intermediate-pressure stage 15' from which elastic fluid, at the higher extraction pressure may be withdrawn from the turbine to a conduit 16. It is formed with a similar opening 17 at a lower, intermediate-pressure stage 17' from which elastic fluid of lower extraction pressure may be withdrawn to a conduit 18. The openings 15 and 17 divide the turbine into a high-pressure section 19, an intermediate-pressure section 21 and a low-pressure section 22, the intermediate-pressure stages 15' and 17' receiving partially expanded motive fluid from the discharge or low-pressure ends of the high-pressure section 19 and the intermediate pressure section 21, respectively.

A diaphragm 23 is provided between the pressure stage 15' and the section 21, and a diaphragm 24 is provided between the pressure stage 17' and the section 22. A passage 25 provides a by-pass around the diaphragm 23 and contains a valve 26 for controlling the flow of motive fluid to the intermediate pressure section 21. Likewise, a passage 27 provides a by-pass around the diaphragm 24, and a valve 28 is interposed in the passage to control the flow of motive fluid to the low-pressure section 22.

It is the function of the valves 26 and 28 to maintain the desired pressures at the pressure stages 15' and 17', and the corresponding openings 15 and 17, by holding back from the lower stages the amount of motive fluid required for extraction. In order to maintain the pressures at the extraction stages and the speed of the turbine substantially constant, the action of these valves and the admission valve 14, upon changes in load and demands for extracted fluid, should be as follows:

Assume first, constant demands and flows;

at the openings 15 and 17, and a change in load on the turbine; for example, an increase in load. All of the valves should be moved in opening direction an amount to provide equal additional flow of motive fluid through all sections of the turbine.

Assuming constant load and constant demand at the opening 17, and an increase in demand at the opening 15, there should be an increased opening of the admission valve 14 and decreased openings of the valves 26 and 28. The increased amount of motive fluid held back by the valve 26 and the increased admission by the valve 14 provide the increased amount of extracted fluid. The valve 28 decreases the admission to the low-pressure section 22 by an amount equal to the decrease in flow through the intermediate-pressure section 21, so that the amount of fluid for extraction through the opening 17 remains the same. A portion of the power development is transferred from the intermediate-pressure section 21 and the low-pressure section 22 to the high-pressure section 19.

Assume now constant load and constant demand at the opening 15, and an increase in demand for fluid at the lower extraction pressure. The openings of the valves 14 and 26 should be increased and the opening of the valve 28 should be decreased. The increased flow through the high-pressure section 19 and the intermediate-pressure section 21 and the increased amount held back by the valve 28 provide the increased amount of fluid for extraction, and a portion of the power development of the low-pressure section 22 is transferred to the high-pressure section 19 and the intermediate-pressure section 21.

In other words, as the demand for extracted fluid increases at any one opening, the valves on the high-pressure side thereof should be moved in opening direction, while the valves on the low-pressure side thereof should be moved in closing direction.

Such operation of the valves is effected by my novel control mechanism which will now be described. The valves 14, 26 and 28 are connected to fluid pressure governors 29, 31, and 32, respectively. Each governor includes a cylinder 33, and a piston 34 operating therein and connected to the associated valve through a lever 35 pivoted to a stationary fulcrum at 36. A spring 37 biases the piston 34 in the direction for opening the associated valve.

Fluid pressure varying as the square of the speed of the turbine is developed by an impeller 38 mounted on the rotor shaft 39. It is conveyed through a conduit 41 to the cylinder 33 of each governor and imposed on the piston 34 in opposition to the spring 37 and in the direction for closing the associated valve.

It is to be understood that any suitable form of governor may be employed, and that it may embody a fluid pressure relay mecha-

nism. Two forms of suitable construction are shown in the patent of O. N. Bryant, Patent No. 1,778,004, granted October 7, 1930.

In order to modify the action of the several governors in accordance with the variations in demand for extracted fluid, I apply an opposing fluid pressure to the opposite side of the piston 34 of each governor, biasing the piston in valve-opening direction. This opposing fluid pressure is derived from a restricted flow, through an orifice 42 which may be located in the piston 34, of fluid under pressure delivered by the impeller 38. It is controlled by regulating the escape of fluid from the upper end of the governor cylinder 33.

The opposing fluid pressures applied to the governors 29, 31, and 32 are controlled by devices, which may be termed compensators, indicated at 43, 44, and 45, respectively. The compensators include pressure relief valves 46, 47, and 48, respectively, communicating with the governors through conduits 49, 51, and 52.

Each compensator further includes a plurality of pressure-responsive elements 53, there being one such element for each opening. The elements 53 bias the pressure relief valves in closing direction, and each element is connected thereto by a lever 54 bearing on a knife edge fulcrum 55. The fulcrum 55 is mounted on a stationary supporting plate 56 and is secured thereto by a screw 57 passing through a longitudinal slot 58 in the supporting plate. The fulcrum may be moved longitudinally of the lever to vary the lever arm ratio.

The compensators are controlled by control devices 59 and 61, associated with the openings 15 and 17, respectively. Each control device provides two fluid pressures which vary in opposite directions to each other upon variation in pressure at the associated opening; that is, one of the fluid pressures increases and the other decreases upon increase in pressure at the opening, while the first decreases and the other increases upon decrease in pressure at the opening.

The control device 59 includes a lever 62 pivoted to a fulcrum 63, the latter being vertically adjustable to vary the setting of the control device. A diaphragm 64 is connected to the lever 62, and is subjected to the pressure of the fluid in the conduit 65, which is communicated to the diaphragm through a conduit 66. A spring 60 biases the lever 62 in opposition to the force of the pressure on the diaphragm 64.

The control device 59 further includes relief valves 66 and 67 which are biased to closed position by springs 68 and 69, the latter being compression springs interposed between the relief valves and spring-holding

members 71 and 72 carried by the lever 62 on opposite sides of the fulcrum 63.

The pressure relief valves 66 and 67 control the escape of fluid from conduits 73 and 74, respectively, each of which is supplied with a restricted flow of fluid under pressure from a branch of the conduit 41, through orifices 75.

The control device 61 is of the same construction as the control device 59, and the corresponding parts thereof bear the same reference numerals with the prime mark (') added. The diaphragm 64' is subjected to the pressure in the conduit 18, communicated thereto through a conduit 65.

The pressure relief valves 66' and 67' control the escape of fluid from conduits 76 and 77, which are also supplied through orifices 75, with a restricted flow of fluid under pressure from the branch of the conduit 41.

The fluid pressure provided by each of the relief valves 66 and 66' varies in the same direction as the fluid pressure imposed on the associated diaphragm, while the pressure provided by the corresponding valve 67 or 67' varies at the same time in the opposite direction. Either of these fluid pressures may be termed the first fluid pressure and the other the second fluid pressure; and for the purpose of the present description, the former is designated the first fluid pressure and the latter the second fluid pressure.

Each of the compensators is subjected to the first fluid pressure of the control device or devices associated with an opening or openings on the high-pressure side of the valve controlled by the compensator, and to the second fluid pressure of any control device or devices associated with an opening or openings on the low-pressure side of the valve controlled by the compensator.

Accordingly, the second fluid pressures of both control devices are communicated through the conduits 74 and 77 to the pressure-responsive elements of the compensator 43, the openings 15 and 17 being on the low-pressure side of the admission valve 14. One of the pressure-responsive elements of the compensator 44 is subjected to the first fluid pressure of the control device 59 communicated through the conduit 73, since the opening 15 associated with the control device 59 is on the high-pressure or up-stream side of the valve 26, and the other pressure responsive element is subjected to the second fluid pressure of the control device 61 communicated through the conduit 77, since the opening 17 associated with the control device 61 is on the low-pressure or down-stream side of the valve 26. The compensator 45 is controlled by the first fluid pressures communicated through the conduits 73 and 76, as both of the openings 15 and 17 are on the high-pressure side of the valve 28.

The operation of the above-described mechanism is as follows:

Assume, first, a change in load on the turbine with the extraction pressures remaining constant, providing constant opposing fluid pressures in the governors. If the load is decreased, the speed increases, and the increased impeller pressure acts on the piston 34 of each governor to move the associated valve in closing direction. The flow to each of the sections 19, 21, and 22 is decreased by a like amount, the difference in flow between the high-pressure section and the intermediate-pressure section 21, which is supplied to the opening 15, remaining constant and the difference between the flow through the intermediate-pressure section 21 and the low-pressure section 22, which is supplied to the opening 17, also remaining constant.

Upon increase in load, the speed decreases. The resulting decreased impeller pressure permits the spring 37 of each governor to move the piston 34 in valve-opening direction. An increase in flow throughout all the sections of the turbine is provided to carry the increased load, the flow through each opening again remaining the same.

Assume, now, a condition of constant demand for extracted fluid at the lower extraction pressure, and an increase in demand for extracted fluid at the higher extraction pressure at the opening 15, the load remaining constant. The increase in demand for the higher pressure extracted fluid is accompanied by a decrease in pressure thereof, which decrease in pressure is communicated through the conduit 65 to the diaphragm 64. The lever is rocked in clockwise direction by the spring 60 an amount determined by the scale of the spring, and the scale effect of the springs 68 and 69. The compression of the spring 68 is decreased, while the compression of the spring 69 is increased, resulting in decreased first fluid pressure in the conduit 73 and increased second fluid pressure in the conduit 74.

The decrease in first fluid pressure of the control device 59 reduces the closing force on the valves 47 and 48 of the compensators 44 and 45 so that said valves effect decrease in the opposing fluid pressures in the governors 31 and 32. The impeller pressure in the governors 31 and 32 now preponderates, and the pistons 34 thereof move the by-pass valves 26 in closing direction.

In response to the increased second fluid pressure provided by the control device 59, the compensator 43 provides increased opposing pressure in the governor 29, and the latter thereupon moves the admission valve 14 in opening direction.

The additional motive fluid held back by the valve 28 and the additional motive fluid admitted by the admission valve 14 supplies the additional high-pressure extracted fluid

to the opening 15. The decrease in power development in the intermediate pressure 21 and the low-pressure section 22, is balanced by the increase in power development in the high-pressure section 19. The closing movement of the valve 28 effects a decrease flow equal to the decrease in flow to the valve 26, so that the amount of extracted fluid supplied to the opening 17 remains constant.

Upon decrease in demand for high-pressure extracted fluid, the pressure thereof increases and the parts of the control mechanism each move in the opposite direction. The flow through the high pressure section 19 is decreased, and the flow through the intermediate-pressure section 21 and the low-pressure section 22 is increased.

Assume, now, an increase in demand for low-pressure extracted fluid, with the demand for high-pressure extracted fluid and the load on the turbine remaining constant. The pressure of the fluid flowing through the opening 17 and the conduit 18 decreases, which decrease is communicated through the conduit 65' to the diaphragm 64'. The lever 62' is rocked in clockwise direction by the spring 50' a corresponding amount providing decreased first fluid pressure in the conduit 76 and increased second fluid pressure in the conduit 77.

The compensators 43 and 44 act in response to the increase in second fluid pressure to provide increased opposed fluid pressures in the governors 29 and 31, and the latter effect increased opening of the admission valve 14 and the by-pass valve 26. The compensator 45 responds to the decreased first fluid pressure by providing decreased opposing fluid pressure in the governor 32, and the latter effects closing movement of the by-pass valve 28.

The increased openings of the valves 14 and 26 are such as to provide equal increases in flow through the high-pressure section 19 and the intermediate-pressure section 21. This increased flow, together with the additional steam held back by the valve 28, supplies the increased demand for low pressure extracted fluid. Said increase in flow is so related to the steam held back by the valve 28 that the decrease in power development by the low-pressure section 22 is balanced by the increase in power development by the high-pressure section 19 and the intermediate-pressure section 21.

Upon decrease in demand for low-pressure extracted fluid, the pressure thereof increases and the parts each move in the opposite direction. The flow through the high-pressure section 19 and the intermediate-pressure section 21 is decreased, and the flow through the low-pressure section 22 is increased. The decrease in power development by the first two sections is balanced by the increase in

power development by the low-pressure section 22.

The proper proportion of valve movement of the various valves in response to a change in pressure at one of the openings is obtained by adjusting the position of each knife edge fulcrum 55 to provide the proper lever arm ratios of the lever 54 which contacts therewith. It is to be understood that suitable well known forms of adjustment may be used throughout the control mechanism.

It will be apparent that the pressure within the region enclosed by an extraction pressure stage and the opening and extraction conduit communicating therewith is substantially the same, or at least varies similarly with changes in demand, and that the pressure for controlling the associated pressure-responsive diaphragm may be taken at any point within that region.

Either or both of the openings 15 or 17 may be utilized to admit motive fluid of suitable pressure to the corresponding stages instead of extracting fluid therefrom. The operation of the parts is exactly the same, although possibly the pressure setting might be slightly changed by varying the vertical position of the fulcrum 53 or 53'.

Assuming admission of motive fluid of suitable pressure to either of the openings, an increase in supply is accomplished by an increase in pressure imposed on the corresponding diaphragm 64 or 64'. The operation is the same as above described, the valves on the low-pressure side of the opening being moved in opening direction in order to utilize the additional supply of relatively low-pressure motive fluid, and the valves on the high-pressure side of the opening being moved in closing direction to compensate for the increased power development on the low-pressure side of the opening. A decrease in supply is accomplished by an increase of pressure, and the valves on the low-pressure side move in closing direction while the valves on the high-pressure side move in opening direction.

While I have shown my invention in but one form, it will be obvious to those skilled in the art that it is not so limited, but is susceptible of various changes and modifications, without departing from the spirit thereof and I desire, therefore, that only such limitations shall be placed thereupon as are imposed by the prior art or as are specifically set forth in the appended claims.

What I claim is:—

1. The combination with a multi-stage prime mover having openings communicating with a plurality of pressure stages therein, and admission valve for controlling the admission of motive fluid to the prime mover and a valve controlling the flow at each opening, of a control mechanism comprising a device associated with each opening and providing a fluid pressure varying in one direc-

tion and another fluid pressure varying in the opposite direction in response to change in pressure at the associated opening, and a means for controlling each valve in response to one of the fluid pressures of each of said devices.

2. The combination with a multi-stage prime mover having openings communicating with a plurality of pressure stages therein, an admission valve for controlling the admission of motive fluid to the prime mover and a valve controlling the flow at each opening, of a control mechanism comprising a device associated with each opening and providing a fluid pressure varying in one direction and a second fluid pressure varying in the opposite direction in response to change in pressure at the associated opening, means providing a third fluid pressure varying as a function of the speed of the prime mover, and means for controlling each valve in response to the third fluid pressure and one of the fluid pressures of each of said devices.

3. The combination with a multi-stage elastic fluid prime mover having openings communicating with a plurality of pressure intermediate stages therein, an admission valve and a valve controlling the flow at each opening, of a control mechanism comprising a device associated with each opening and providing a fluid pressure varying in one direction and a second fluid pressure varying in the opposite direction in response to change in pressure at the opening, means providing a third fluid pressure varying in response to change in speed of the prime mover, and means for controlling each valve comprising means providing a fourth fluid pressure varying in response to one of the fluid pressures of each of said devices and a governor responsive to the fourth fluid pressure and to the third fluid pressure for controlling the valve.

4. The combination with a multi-stage elastic fluid prime mover having openings communicating with a plurality of pressure stages therein, an admission valve for controlling the admission of motive fluid to the prime mover and a valve controlling the flow at each opening, of a control mechanism comprising a device associated with each opening and providing a first fluid pressure varying in a given direction and a second fluid pressure varying in the opposite direction in response to change in a given direction in pressure at the opening, and means for controlling each valve in response to the first fluid pressure of each device at an opening on the high pressure side of the valve and to the second fluid pressure of each device at an opening on the low pressure side of the valve.

5. The combination with a multi-stage elastic fluid prime mover having openings communicating with a plurality of pressure stages therein, an admission valve and a

valve controlling the flow at each opening, of a control mechanism comprising a device associated with each opening and providing a first fluid pressure varying in a given direction and a second fluid pressure varying in the opposite direction in response to change in a given direction in the pressure at the opening, means providing a third fluid pressure varying in response to change in speed of the prime mover, and means for controlling each valve comprising means providing a fourth fluid pressure varying in response to the first fluid pressure of each device at an opening on the high pressure side of the valve and to the second fluid pressure of each device at an opening on the low pressure side of the valve and a governor responsive to the fourth fluid pressure and to the third fluid pressure for controlling the valve.

In testimony whereof, I have hereunto subscribed my name this 3rd day of July, 1930.
